DUPLEX ALBUM LEAF FOR PHOTOGRAPHIC PRINTS

Walter A. McCabe, East Haddam, Conn., assignor to Ernestine McCabe, East Haddam, Conn.

Application August 18, 1950, Serial No. 180,193

2 Claims. (Cl. 129—20)

1

The invention relates to a duplex album leaf for mounting and framing photographic prints, the leaf being adapted for the mounting and framing of two prints at the respective sides thereof. A plurality of similar leaves may be secured in place in an album binder or cover which may be of conventional construction and which does not constitute a part of the present invention.

It has been the prior practice in this art to provide framing mats which are attachable to the main body of the leaf and which carry or are combined with envelopes for containing the prints. The prints are placed in the envelopes with the expectation that they will be properly exposed through the framing openings in the mats. However, the envelopes do not closely fit the prints and furthermore they are open at one or both ends, the result being that the prints are not accurately located and held. Either initially or after use the prints are out of proper register with the framing openings and the results are quite unsatisfactory.

One of the objects of the invention is to provide an album leaf having a body with front and rear sections, and having means on each body section for accurately locating and holding a print thereon in vertical position or in horizontal position, such locating and holding means being entirely independent of the framing mats. In accordance with the invention the framing mats merely frame the prints and cover the edges thereof without being relied upon or used to locate the prints or to hold them in place.

Another object of the invention is to provide an album leaf having the described characteristics and having an improved main body formed by properly blanking and folding a single sheet of cardboard or other suitable material.

Still another object of the invention is to provide an album leaf having the described characteristics and having novel and advantageous means for locating and holding the prints on the sections of the body.

Still other objects of the invention will be apparent from the drawing and from the following description and claims.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

2

On the drawing:

Fig. 1 is a front view of a blank which, after folding, constitutes the body of an album leaf embodying the invention.

Fig. 2 is a front view of the hinge structure forming a part of the album leaf.

Fig. 3 is a front view of one of the framing mats.

Fig. 4 is a front view of an album leaf with a picture therein but without the framing mat.

Fig. 5 is a view similar to Fig. 4 with the framing mat in place.

Figs. 6, 7, 8, 9 and 10 are enlarged fragmentary sectional views taken respectively along the lines 15 6—6, 7—7, 8—8, 9—9 and 10—10 of Fig. 4.

Fig. 11 is a view similar to Fig. 9 but showing an alternative construction.

Fig. 12 is an enlarged fragmentary sectional view taken along the line 12—12 of Fig. 5.

20 A duplex album leaf embodying the invention includes a body which comprises two similar rectangular front and rear cardboard sections which are parallel with each other and which are preferably spaced apart by a small distance. The term "cardboard" is used in a generic sense and is intended to include any suitable relatively stiff but nevertheless somewhat flexible sheet material.

The two body sections may be variously formed and connected, but as shown in Fig. 1 there is 30 preferably provided a blank cardboard sheet 10 which upon folding constitutes the body of the album leaf. The blank 10 comprises two similar front and rear sections 12 and 14 which are integral with each other and which are connected along a vertical folding zone. The said sections 12 and 14 are of the same size and are preferably approximately square. Vertical scoring is provided at the folding zone between the two sections to permit the section 14 to be folded rear-

40 wardly and toward the left along the scoring so as to be positioned at the rear of the section 12. The folded blank is shown in Fig. 4. Preferably a single score line 16 is provided at the front and two spaced score lines 18, 18 are provided 45 at the rear. The arrangement and spacing of the score lines causes the sections 12 and 14 to be spaced from each other after folding. The two sections are spaced apart by a distance approximately equal to the thickness of the blank.

50 The last above-mentioned spacing is shown in Fig. 6. It will be understood however that in Fig. 6 and in the other cross sectional views the dimensions in the direction of thickness are not exactly to scale, being in most instances somewhat exaggerated.

The blank 10 is provided at the top and at the bottom with integral tabs 20 and 22 which extend respectively upwardly and downwardly. Each tab is connected to one of the body sections and preferably they are connected to the same section, as for instance the section 12. The tab 20 is adapted to be folded rearwardly and downwardly along a score line 24 to a position behind and in face-to-face relationship with the section 12 as indicated at 20° and is more clearly shown in Fig. 7. Similarly, the tab 22 is adapted to be folded rearwardly and upwardly along a score line 26 to a position behind and in face-to-face relationship with the section 12 as indicated at 22°.

The tabs 20 and 22 are first folded as described to the positions 20^a and 22^a and thereafter the section 14 is folded as described to bring it into engagement with the rear faces of the folded tabs, as shown in Fig. 7. The section 14 is held in engagement with the tabs by pasting. When the blank has been folded and pasted as described, the two sections 12 and 14 thereof are adjacent each other but are spaced apart by a distance equal to the thickness of the tabs. After folding and pasting metallic corner clips 28, 28 may be applied at the upper and lower right corners.

As shown more particularly in Figs. 1 and 8, the album leaf also includes a hinge structure generally indicated at 30. The hinge structure includes a long narrow binding strip 32 of cardboard or other suitable stiff material, this strip being relatively thick and extending vertically from the top to the bottom of the hinge structure. A vertical zone 34 of flexible material such as cloth or paper is provided adjacent the binding strip 32. Preferably and as shown, a sheet 36 of flexible material is wrapped around the strip 32, being pasted thereto. Portions of the sheet 36 extend toward the right from the strip 32, these portions being in contact along the said vertical zone 34 and being pasted to each other. A relatively thin spacer strip 38 is provided, this strip being formed of cardboard or other suitable stiff material and extending from the top to the bottom of the hinge structure. The right portions of the flexible sheet 36 are at the front and rear faces of the strip 38 and are pasted thereto. Holes 40, 40 are provided in the strip 32 and in the flexible sheet 36 for receiving studs or posts forming a part of an album binder or cover which may be of conventional design. It will be seen that the contacting portions of the flexible sheet 36 at the zone 34 between the strips 32 and 38 constitute a flexible hinge element.

After the blank 10 has been folded and pasted as described and after the hinge structure has been formed as described, the right portion of the hinge structure is inserted in the space at the left portion of the folded blank between the spaced front and rear sections 12 and 14 thereof, as shown in Figs. 4 and 8. The parts are pasted so as to be held in their assembled relationship. The binding strip 32 in the left portion of the hinge structure is adjacent and spaced from the vertical edge of the main body and the flexible material in the zone 34 is interposed between the binding strip and the said edge of the body. Thus the main body comprising the folded blank is hingedly connected at the zone 34 with the left portion of the hinge structure, which portion of the hinge structure is adapted to be connected with an album binder or cover.

The front body section 12 is provided with four similar cuts 42, 42 which are preferably arcuate. The cuts 42, 42 are near the corners of the section 12 and are at the corners of a square. Each 5 of the cuts 42, 42 has its concave side toward the center of the section 12, and each cut outlines a deflectable tongue 44. Preferably a notch 46 is provided at the concave side of each cut 42 and within the tongue 44. Similar cuts, tongues and 10 notches are provided in the rear body section 14. In order to provide sufficient spaces for the several cuts 42, 42, the tabs 20 and 22 are preferably relatively narrow near their ends. For the same 15 reason the spacing strip 38 of the hinge structure is preferably relatively narrow near its ends. The cuts 42, 42 in each body section are adapted for receiving the corner portions of a framing mat as hereinafter described.

Means are provided on the respective body sections 12 and 14 for directly locating and holding on the outer face of each of them a photographic print having a predetermined size smaller than the square at the corners of which the cuts 42, 42 are located. The last aforesaid means are 20 adapted for locating prints of oblong shape and each of the said means is constructed and arranged to hold the corresponding print either in horizontal position in the same general location or in vertical position. Each print is accurately 25 located and is located and held entirely independently of the corresponding framing mat.

The means for locating and holding the photographic prints may be varied but the said means preferably comprises two pairs of notches in each 30 of the respective body sections, the notches of one pair in each section being positioned to receive diagonally opposite corner portions of a print in horizontal position and the notches of the other pair in each section being positioned 35 to alternatively receive diagonally opposite corner portions of a print in vertical position. Referring particularly to Fig. 1, the notches in the body section 12 for locating and holding a print such as 48 in horizontal position are shown 40 at 50 and 52 and the notches for locating and holding an alternative print 54 in vertical position are shown at 56 and 58. Similarly the body section 14 is provided with notches 60 and 62 for 45 locating and holding a second print 64 in horizontal position and with notches 66 and 68 for locating and holding an alternative print in vertical position. From the foregoing description it will be apparent that two photographic prints of the same predetermined size and shape 50 may be mounted on the album leaf, one at the front thereof and the other at the rear thereof. Either print may be in horizontal position or in 55 vertical position.

Transparent cover sheets 70 and 72 having the 60 same size as the prints are ordinarily placed at the fronts of the prints to protect them, the prints and the cover sheets being both located and held in place by the notches. The transparent sheets are shown in Figs. 9 and 10. Ordinarily each print and the corresponding cover sheet are put in place at the same time, one 65 corner being first inserted in one notch. The print and cover sheet are flexed to enable the diagonally opposite corner to be inserted in the other notch.

In order that the prints and the cover sheets may remain flat after entry in the notches, the body section is provided with raised or offset portions 74, 74 adjacent the respective notches. One 75 offset portion 74 is shown in Fig. 9, and another

offset portion 74 is shown in Fig. 10. The said offset portions provide recesses into which the corner portions of the prints and cover sheets extend while remaining flat, thus avoiding any permanent flexing of the cover portions with resultant outward bulging of the main portions of the prints and cover sheets.

It will be observed particularly from Fig. 4 that the notches 60, 62, 66 and 68 and the corresponding offset portions 74, 74 of the body section 14 are so located that they are out of register with the notches 50, 52, 56 and 58 and the corresponding offset portions 74, 74 of the body section 12. This avoids the increased total thickness of the album leaf which would result if the several offset portions 74, 74 of the two body sections were in register with each other.

While it is ordinarily sufficient to engage each print and the corresponding cover sheet only at the diagonally opposite corners thereof, it may under some circumstances be desirable to provide eight additional notches 76 so that each print and cover sheet may be held at all four corners, either in horizontal position or in vertical position. The drawing does not show all of the eight additional notches 76 but one such notch is shown in Fig. 11, which is similar to Fig. 9 except for the additional notch 76.

Two similar front and rear framing mats 78, 78 are provided, one of them being shown in Fig. 3. Each mat 78 is square, except that the corners are preferably rounded. A rectangular opening 80 is provided in each mat 78, this opening having approximately the same size and shape as the prints 48, 54 and 64 but slightly smaller. Each mat may be ornamentally embossed at the edges of the opening 80.

After a print 48 or 54 and its cover sheet have been positioned in the locating notches in the body section 12 as described, one of the framing mats is put in place over it as shown in Fig. 5, the mat being turned so that the opening 80 is horizontal or vertical as required. In the positioning of the framing sheet the corner portions thereof are inserted in the cuts 42, 42, the tongues 44, 44 being slightly flexed as shown in Fig. 12. It will be understood that the mat 78 must be flexed in order to permit its corner portions to be inserted as described. Similarly, after the print 64 or an alternative vertical print has been positioned in the locating notches in the body section 14, the other framing mat is put in place over it, the mat being turned so that the opening 80 is horizontal or vertical as required.

The described spacing between the body sections 12 and 14 provides room for the insertion of the corner portions of one framing mat 78. When the second framing mat is put in place the immediately adjacent portions of the two body sections 12 and 14 are forced apart slightly as shown.

The framing mats cover the edges of the prints and also cover the several print locating notches, but they do not in any way serve to locate or hold the prints. The prints are located and held solely by the several notches in the body sections.

The invention claimed is:

1. In a duplex album leaf for photographic prints, the combination of a body comprising two similar rectangular front and rear cardboard sections parallel with each other which sections

are firmly connected with each other, means for spacing the major portions of the areas of said sections, cuts in each of the body sections near the corners thereof and at the corners of a square, 5 two pairs of notches in each of the respective body sections for directly locating and holding on the outer face of each of them a photographic print having a predetermined size smaller than the corresponding aforesaid square and having 10 an oblong shape, the notches of one pair in each section being positioned to receive diagonally opposite corner portions of a print in horizontal position and in a predetermined general location and the notches of the other pair in each section being positioned to alternatively receive diagonally opposite corner portions of a print in vertical position in the same general location, and front and rear square cardboard framing mats each of such size that it may be 15 connected to the outer face of the corresponding body section by the insertion of its corner portions in the said cuts in the said body section and be accommodated in the space between said sections, each mat having an oblong opening 20 therein which is of approximately the same size and shape as the corresponding print and which is so located that the said print is visible through the said opening when the print is located and held by the corresponding notches and when the 25 corner portions of the mat are inserted in the corresponding cuts and each mat by reason of its square shape being adapted to be connected to its body member with the oblong opening in the said mat either in horizontal position or 30 in vertical position according to the position of the corresponding print.

2. A duplex album leaf for photographic prints as set forth in claim 1, wherein each body section is provided adjacent each print receiving notch with an outwardly offset portion which provides a recess into which the corresponding corner portion of the print may extend with the print flat, and wherein the print receiving notches and the corresponding offset portions of each body 40 section are out of register with the print receiving notches and the corresponding offset portions of the other body section.
